UNITED STATES PATENT OFFICE.

ARTHUR O. JENNINGS, OF SOUTHPORT, CONNECTICUT, ASSIGNOR OF ONE-HALF TO MOLLY ELLIOTT SEAWELL, OF WASHINGTON, D. C.

CAB-REGISTER.

SPECIFICATION forming part of Letters Patent No. 334,720, dated January 26, 1886.

Application filed September 26, 1885. Serial No. 172,246. (No model.)

To all whom it may concern:

Be it known that I, ARTHUR O. JENNINGS, a resident of Southport, in the county of Fairfield and State of Connecticut, have invented 5 an Improved Cab-Register, of which the following is a full, clear, and exact description, reference being made to the accompanying drawings, in which—

Figure 1 represents a side view, partly in 10 section, of a cab having my improved register. Fig. 2 is a face view of the register. Fig. 3 is a side view of the same. Fig. 4 is an enlarged face view of the internal mechanism of the register. Fig. 5 is a cross-section thereof 15 on the line *c c*, Fig. 4; and Fig. 6 is a detailed top view, partly in section, of the mechanism for arresting the motion of the register.

This invention relates to a new clock-work register which is to be placed in cabs and 20 analogous places to register the time during which the vehicle was in use, so that the owner thereof and also the passenger carried may be protected against any possible dishonesty 25 on the part of the driver.

The invention is applicable also as a billiard-register, and for similar purposes; and 30 it consists in the new combination of parts hereinafter more clearly specified.

In the drawings, the letter *A* represents the 35 frame of the clock-work register, the same being put into a case, *B*, which has a hinged lid or cover, *C*, with a glass front, through which the dial and hands of the register can be seen, and this hinged lid is intended to be held 40 closed by a suitable lock, *D*. The frame *A* carries a suitable clock-work for revolving a center arbor, *a*; which carries on the outer side of the dial *b* a hand, *E*. This hand is to be revolved over the graduated scale on the 45 dial, so as to indicate in the example shown the number of minutes during which the cab is in use by any one passenger up to three hundred and sixty minutes, or six hours. The hand *E* is fitted upon a sleeve, *d*, which surrounds the arbor *a* frictionally, so as to be 50 carried around by the same, but nevertheless to be capable of independent rotary motion. The sleeve *d* has fastened to it a heart-shaped cam, *e*. This cam is below a push-button or slide, *F*, which extends through the case *B*, and which carries a little friction-roller, *f*, at

its lower end. A spring, *g*, holds the push-button *F* normally in the elevated position in which it is represented in Figs. 4 and 5. The cam *e* is mounted upon the sleeve *d* in such 55 manner with reference to the position of the hand *E* that when the hand points to zero, as in Fig. 2, the concave part of the cam will be on top, as in Fig. 4, and the pointed part of the cam will project downward; or, to be 60 more specific, in the zero position the concave part of the cam will be aligned with and behind the hand *E*. A pinion, *h*, on the arbor *a* meshes into a toothed wheel, *i*, the arbor of which, *j*, extends through the dial *b*. 65 Upon this arbor *j* is fitted a frictional tube, *k*, which carries on the outer side of the dial a hand, *G*, and on the inner side of the dial a pinion, *l*. The hand *G* is placed on the face of the dial *b*, over a graduated scale, which is 70 intended to indicate the hours and fractions of hours during which the cab is in use by a series of passengers. This is in contradistinction to the use to which the hand *E* is put, which is only to indicate the time during which 75 the cab has been at the disposal of any one passenger.

The wheels which transmit the motion of the clock mechanism to the hand *G* are so regulated as to their respective sizes that the 80 hand *G* will pass over a space which is marked for, say, one hour, in the same period of time during which the hand *E* will pass over a space marked for sixty minutes on its scale; hence the hand *E* may well be called the 85 "minute-hand" and the hand *G* the "hour-hand."

The pinion *l* in the normal position of the mechanism, which is shown in Fig. 5, is not in gear with any wheel, but there is in the mechanism a toothed wheel, *m*, fitted upon an arbor, *n*, and pressed outward by a spring, *o*, said toothed wheel carrying a square hub, *p*, which extends through and beyond the dial *b*. Whenever the key with which the clock 95 mechanism can be wound is applied to this hub *p*, which it fits, the wheel *m* can be pressed against the spring *o* into line and gear with the pinion *l*, and then the key, still holding the wheel *m* under pressure in gear, can be 100 turned to set the hand *G* to zero, or to any other place on its dial.

To the frame A is pivoted at *q* a lever, H, which projects beyond the case B, and which carries within the case B a flexible arm or projection, *r*, which can be brought against the face of the balance-wheel I of the clock mechanism to arrest the motion thereof.

Fig. 4 shows the lever H by full lines in the position for stopping the clock mechanism, and by dotted lines in the position for relieving the balance-wheel I from the elastic arm *r*, and thus in the position in which the clock mechanism will be operative and in motion.

The operation of this apparatus is as follows: Before the cab starts out in the morning the proprietor, opening the lock D, with the assistance of the key sets the hand G to zero, in the manner already described. He also sets the hand E to zero by pressing the push-button F downward, which causes it to reach the cam *e*, and to turn that cam into the zero position shown in Fig. 4, and with it the hand E. The case B is now locked and the driver sent on his way. The clock during this time is not in motion, the lever H being in the position shown by full lines in Figs. 2 and 4. As soon as a passenger enters, the driver is to put the lever H into the position shown by dotted lines, so as to set the clock mechanism to work. The whole contrivance should be placed in the cab so that the passenger can see the dial and be informed by the hand E of the exact time the vehicle is occupied by him. As soon as the passenger leaves the cab the driver is to put the lever H back into the stopping position. The dial will now show the passenger for what length of time he has to pay, after which the driver depresses the push-button, and thereby brings the hand E back to zero, ready for the like use by a new passenger; but the hand G is by this motion of the push-button not brought back to zero. It stays to indicate the time occupied by the first passenger, and when afterward the clock is again set in motion for a second passenger the hand G will start again, and thus add up the several periods of time during which the cab is occupied by passengers; hence the inspector or proprietor can by a glance at the hand G ascertain the total time during which the cab was used by passengers.

It will be impossible for the driver to interfere with the action of the hand G, except to his own disadvantage in failing to set the clock-work in motion as soon as the period for which a passenger should pay commences to run.

As already stated, this invention is not only applicable to cab-registers, but may with profit be used for many analogous purposes.

I disclaim interposing a pivoted lever between the push-button, which has the friction-roller *f*, and the heart-shaped cam.

What I claim is—

1. The combination of the arbor *a* with the sleeve *d*, hand *E*, and heart-shaped cam *e*, said hand *E* and cam *e* being rigidly attached to said sleeve, with the sliding push-button *F*, having friction-roller *f*, and retracting-spring *g*, substantially as herein shown and described. 70

2. The combination of the clock mechanism and its center arbor, *a*, with the sleeve *d*, cam *e*, hand *E*, sliding push-button *F*, carrying the roller *f*, balance-wheel *I*, pivoted lever *H*, and elastic projection *r* thereon, all substantially a 75 and for the purpose herein shown and described.

3. The combination of the hand *G*, its arbor *j*, sleeve *k*, and pinion *l*, and dial *b*, in front of which said hand *G* is placed, with the sliding wheel *m*, having hub *p*, said hub projecting through an aperture of the dial *b*, all arranged to allow the wheel *m* to be set in gear with the pinion *l*, for the purpose of moving the hand *G* whenever access to said dial is permitted, 85 as specified.

4. In a cab-register, the combination of the case B and hinged lid C with the clock-work having arbor *a*, hand *E*, sleeve *d*, cam *e*, push-button *F*, friction-roller *f*, spring *g*, lever *H*, 90 elastic arm *r*, balance-wheel *I*, pinion *h*, toothed wheel *i*, arbor *j*, sleeve *k*, hand *G*, pinion *l*, toothed wheel *m*, angular hub *p*, spring *o*, and arbor *n*, substantially as herein shown and described.

ARTHUR O. JENNINGS.
